UNITED STATES PATENT OFFICE.

JOHN H. LLOYD, OF TOLEDO, OHIO.

DESIGN FOR A MONUMENT.

SPECIFICATION forming part of Design No. 23,193, dated April 10, 1894.

Application filed February 3, 1894. Serial No. 499,034. Term of patent 7 years.

To all whom it may concern:

Be it known that I, JOHN H. LLOYD, a citizen of the United States, residing at Toledo, Lucas county, Ohio, have invented and proposed a new and original Design for a Monument, of which the following is a specification, reference being had to the accompanying drawings, made part hereof, in which—

Figure 1, is a side elevation of a monument showing my design; Fig. 2, an end elevation of the same, and Fig. 3, a perspective view of the same.

The leading feature of my design consists in a three part monument having the rock-faces, tooled margins, panel and rounded corners hereinafter pointed out.

In the drawings, A is the base of the monument, the sides and ends of which base are rock-faced. The upper corners of base A are beveled to form a "wash" *a* the surface of which is smooth. Supported upon the lower base is a second and smaller base, B, which also has rock-faced sides and ends, and smooth, beveled, upper corners or "wash" *b*. The

third member of the monument, the die C, *25* rests upon the second base B. This die has rock-faced sides and ends and a beveled top, the four, smooth, inclined surfaces meeting at apex line, *d*. One or both sides of the die are provided with an inscription-panel, *e*. The *30* margins *f*, of the vertical faces of base B and die C, except the lower horizontal margin of base B, are tooled or smooth, as shown in the drawings. The beveled "wash" of base B and of die C are connected with the upper *35* horizontal, tooled margins of these parts by gently rounded corners *g*, it being a special feature of my design to substitute curved lines for the usual angles formed by the meeting of the vertical faces and the beveled tops *40* of the pieces forming this class of monuments.

What I claim is—

The design for a monument herein shown and described.

JOHN H. LLOYD.
